CLAIM

The ornamental design for a wind turbine blade, as shown and described.

DESCRIPTION

FIG. 1 is a top perspective view of the design.

FIG. 2 is a bottom perspective view of the design.

FIG. 3 is a top perspective view of the design, from a point higher than shown in FIG. 1.

FIG. 4 is a side view of the design.

FIG. 5 is a side view of the design shown in FIG. 4, slightly rotated.

FIG. 6 is a side view of the design shown in FIG. 5, slightly rotated.

FIG. 7 is a top view, looking straight down on the design; and,

FIG. 8 is a bottom view, looking straight up on the design. In the drawings, the broken lines are for the purpose of illustrating portions of the wind turbine blade that form no part of the claimed design.
